[57] CLAIM

The ornamental design for a perfume bottle, as shown and described.

DESCRIPTION

FIG. 1 is a front elevational view of a perfume bottle showing my new design;

FIG. 2 is a right side view thereof;

FIG. 3 is a rear elevational view thereof;

FIG. 4 is a left side view thereof;

FIG. 5 is a top plan view thereof;

FIG. 6 is a bottom plan view thereof; and

FIG. 7 is a fragmentary cross section taken along line 7—7 of FIG. 4, looking in the direction of the arrows.
